UNITED STATES PATENT OFFICE

160,987

PEDAL CONTROL

Elbern H. Alkire, Easton, Pa.

Application December 5, 1949, Serial No. 6,419

Term of patent 14 years

(Cl. D14—6)

To all whom it may concern:

Be it known that I, Elbern H. Alkire, a citizen of the United States residing at Easton, in the county of Northampton and State of Pennsylvania, have invented a new, original, and ornamental Design for Pedal Controls, of which the following is a specification, reference being had to the accompanying drawing, forming part thereof.

Fig. 1 is a side elevation of a pedal control;

Fig. 2 is a rear elevation of the pedal control shown in Fig. 1;

Fig. 3 is a front elevation of the pedal control shown in Figs. 1 and 2, showing my new design.

I claim:

The ornamental design for a pedal control, as shown.

ELBERN H. ALKIRE.
